[57] CLAIM

The ornamental design for a pair of shoe uppers, as shown and described.

DESCRIPTION

FIG. 1 is a rear perspective view of the right shoe of a pair of shoe uppers, showing our new design;

FIG. 2 is the right side elevational view of the right shoe upper;

FIG. 3 is a left side elevational view of the left shoe upper; FIG. 4 is a left side elevational view of the right shoe upper, the right side elevational view of the left shoe upper being a mirror image thereof;

FIG. 5 is a top plan view of a pair of shoe uppers;

FIG. 6 is a front elevational view thereof; and,

FIG. 7 is a rear elevational view thereof.

The broken line showing of a shoe sole in FIGS. 1-7 is for illustrative purposes only and forms no part of the claimed design.
